DESIGN FOR A CASING FOR COAL STOKERS OR THE LIKE

James A. Perkins, Longmeadow, Mass.

Application April 18, 1935, Serial No. 56,454

Term of patent 3½ years

To all whom it may concern:

Be it known that I, James A. Perkins, a citizen of the United States, residing at Longmeadow, in the county of Hampden and State of Massachusetts, have invented a new, original, and ornamental Design for a Casing for Coal Stokers or the like, of which the following is a specification, reference being had to the accompanying drawing, forming part thereof.

Fig. 1 is a top plan view of a casing for a coal stoker or the like;

Fig. 2 is a side elevational view of the casing shown in Fig. 1;

Fig. 3 is an end elevational view of the casing shown in Fig. 1; and

Fig. 4 is a perspective view of the casing shown in Figs. 1 to 3 inclusive.

I claim:

The ornamental design for a casing for coal stokers or the like, as shown.

JAMES A. PERKINS.
